The ornamental design for a battery pole, as shown and described.

DESCRIPTION

FIG. 1 is a front elevational view of an embodiment of a battery pole;

FIG. 2 is a rear elevational view of the embodiment of the battery pole;

FIG. 3 is a top plan view of the embodiment of the battery pole;

FIG. 4 is a bottom plan view of the embodiment of the battery pole;

FIG. 5 is a left side elevational view of the embodiment of the battery pole;

FIG. 6 is a right side elevational view of the embodiment of the battery pole;

FIG. 7 is a first perspective view of the embodiment of the battery pole;

FIG. 8 is a second perspective view of the embodiment of the battery pole;

FIG. 9 is a third perspective view of the embodiment of the battery pole; and,

FIG. 10 is a fourth perspective view of the embodiment of the battery pole.

The broken lines shown in the drawings are included for the purpose of illustrating environmental structure and form no part of the claimed design.
